UNITED STATES PATENT OFFICE

107,232

DESIGN FOR A FRATERNAL CHARM OR SIMILAR ARTICLE

William E. Holler, Birmingham, Mich.

Application July 26, 1937, Serial No. 70,667

Term of patent 7 years

To all whom it may concern:

Be it known that I, William E. Holler, a citizen of the United States, residing at Birmingham, in the county of Wayne, State of Michigan, have invented a new, original, and ornamental Design for a Fraternal Charm or Similar Article, of which the following is a specification, reference being had to the accompanying drawing, forming a part thereof.

Figure 1 is a front elevation of a fraternal charm or similar article showing my new design.

I claim:

The ornamental design for a fraternal charm or similar article as shown.

WILLIAM E. HOLLER.
